UNITED STATES PATENT OFFICE

FREDERICK F. ZEIER, OF CHICAGO, ILLINOIS, ASSIGNOR TO UNION SPECIAL MACHINE COMPANY, OF CHICAGO, ILLINOIS, A CORPORATION OF ILLINOIS

THROAT-PLATE SUPPORT FOR SEWING MACHINES

Application filed August 29, 1928. Serial No. 302,874.

The invention relates to new and useful improvements in throat plate supports for sewing machines of the flat work support type.

An object of the invention is to provide a support for the throat plate so that the cloth plate may be removed from the machine without disturbing the throat plate, and therefore, the machine operated for stitching without the cloth plate in place.

A further object of the invention is to provide a support for the throat plate wherein the throat plate is rigidly supported at the front and rear sides thereof by a member which is rigidly supported on the bed of the machine.

In the drawings:-

Fig. 1 is a plan view of a portion of a machine embodying the improvements and showing in broken lines the supporting means for the throat plate.

Fig. 2 is a sectional view on the line 2—2 of Fig. 1, the feeding mechanism being omitted.

Fig. 3 is a sectional view on the line 3—3 of Fig. 1 and showing the bridging support for the throat plate so as to give ample space for the feed bar.

Fig. 4 is a sectional view on the line 4—4 of Fig. 1 showing the support for the throat plate at the end thereof and the manner in which the throat plate bridges the feed dog and loopers.

Fig. 5 is a view of a portion of the machine from the front thereof showing the overhang of the support for the throat plate and the relation of the loopers thereto.

Fig. 6 is a vertical sectional view through the supporting post in a plane parallel with the line of feed.

The invention is directed to a throat plate support for sewing machines, and more particularly to a sewing machine of the type wherein there is a flat work support. The supporting bed is provided with the usual bracket formed integral therewith in which the main shaft of the machine is journaled. This supporting bracket serves as one of the supporting means for the supporting member which carries the throat plate. Spaced

from this supporting bracket is a supporting post which is disposed on the opposite side of the feed bar from the bracket and this post serves as an additional supporting means for the support which carries the throat plate. The support carrying the throat plate is provided with a portion which extends lengthwise of the bracket and said portion is firmly secured to the bracket.

It is also provided with spaced projection portions, one in front of the needle and the other in rear thereof. The rear projecting portion is mounted on the upper end of the post carried by the bed and this post together with the bracket serves as a supporting means for this support for the throat plate. The throat plate bridges the space between the projecting portions of the support and is secured to said projecting portions. The projecting portion at the front of the support for the throat plate overhangs the bracket so as to give freedom for the looper mechanism.

Referring more in detail to the drawings, the invention is shown as applied to a sewing machine which includes a supporting bed 1 which may be of the usual construction. Extending upwardly from the supporting bed is a bracket 2 which is formed integral with the bed. The main shaft, indicated at 3, is journaled in this bracket. Mounted on top of the bracket 2 is the supporting member 4 for the throat plate. This supporting member 4 includes a portion which extends lengthwise of the upper end of the bracket 2 and said support projects beyond said bracket slightly. The support is secured to the bracket by screws 5, 5. Spaced from the bracket 2 is a post 6 which is rigidly attached to the bed of the machine. The feed bar is disposed between this bracket 2 and the post 6. The feed bar is indicated in Fig. 3 of the drawings at 7. Said feed bar carries a feed dog 8. The feed bar is raised and lowered and moved back and forth by the usual operating means therefor.

The support 4 for the throat plate is provided with a laterally projecting portion 9. Said laterally projecting portion 9 extends over the top of the post 6 and is secured there-

to by a suitable screw 10. As an additional means for holding the support on the bracket and post pins 10a have been provided which are respectively integral with the bracket and post and these pins extend into suitable recesses formed in the support.

The support 4 is also provided with a laterally projecting portion 11. The laterally projecting portion 11 is spaced from the projecting portion 9. The projecting portion 9 is well in rear of the needle and the feed dog, while the projecting portion 11 is well in front of the needle and the feed dog. The throat plate is indicated at 12 in the drawings. Said throat plate is provided with the usual feed slots 13, 13 and the needle openings 14 through which the needles pass. The throat plate at its rear end rests on the projecting portion 9 and is secured thereto by screws 16. The projecting portion 11 overhangs a portion of the looper operating mechanism. While I have shown the support 4 as mounted on the bracket at one side of the line of feed and on a post at the other side of the line of feed, it will be understood that other ways may be provided for mounting this support which carries the throat plate. The essential feature resides in the provision of some rigid supporting means for this member and the providing of the member with spaced projecting portions one in front of the needles and the other in rear thereof on which the throat plate may be mounted.

The loopers are indicated at 17 in the drawings. These loopers are mounted on a looper carrier which is oscillated by a suitable link 19. The loopers are, of course, located beneath the throat plate, as clearly indicated in Fig. 4. The throat plate bridges across from one projecting member 9 to the other projecting portion 11. The support for the throat plate is firmly secured to the bracket 2 and to the post 6 and this serves as a sole supporting means for the member which carries the throat plate. By placing the post 6 well to the right of the line of feed and the supporting bracket 2 well to the left of the line of feed, a very rigid support is provided for the throat plate. The cloth plate is indicated in part at 20 in Fig. 1 of the drawings. The cloth plate rests upon the support for the throat plate and is secured thereto by a suitable screw 21. The cloth plate extends about the throat plate and serves as a support for the material being stitched as it passes onto and off from the throat plate. This cloth plate, as noted, is mounted on the support for the throat plate and the support for the throat plate also serves in part as a support for the cloth plate.

Other supporting means is also provided for the cloth plate. By releasing the screws, the cloth plate can be removed from the machine and without in any way interfering

with the throat plate, the throat plate remaining attached to the supporting member 4 therefor.

Thus it is that the cloth plate can be removed and the machine operated for stitching with all of the parts beneath the cloth plate readily accessible for adjustment if desired.

It is obvious that minor changes in the details of construction and the arrangement of the parts may be made without departing from the spirit of the invention as set forth in the appended claims.

Having fully described my invention, what I claim as new and desire to secure by Letters Patent, is:

1. In a sewing machine a supporting bed, a bracket formed integral therewith and disposed at one side of the line of feed, a supporting post disposed at the other side of the line of feed and in rear of the needles, a supporting member mounted on said bracket and having an integral lateral projection in rear of the needles resting thereon and secured to said supporting post and bridging the feed bar of the machine, said support having a laterally projecting portion in front of the needles overhanging the bracket, a throat plate secured at its rear end to the laterally projecting portion of the support in rear of the needles and at its front end to the laterally projecting portion of the support in front of the needles.

2. In a sewing machine a bed, a bracket formed integral therewith and disposed at one side of the line of feed, a supporting post rigidly attached to said bed and disposed at the other side of the line of feed, a support mounted on said bracket and post and having spaced laterally projecting portions, a throat plate secured to said laterally projecting portions and bridging the space between the same, a cloth plate, and means for supporting said cloth plate independently of the throat plate whereby the cloth plate may be removed from the machine without disturbing the throat plate and the machine operated for stitching.

3. In a sewing machine a supporting bed, a bracket formed integral therewith and disposed at one side of the line of feed, a supporting post disposed at the other side of the line of feed and in rear of the needles, a supporting member mounted on said bracket and having an integral lateral projection in rear of the needles resting thereon and secured to said supporting post and bridging the feed bar of the machine, said support having a laterally projecting portion in front of the needles overhanging the bracket, a throat plate secured at its rear end to the laterally projecting portion of the support in rear of the needles and at its front end to the laterally projecting portion of the support in front of the needles, a cloth plate, and means

for supporting said cloth plate independently of the throat plate whereby the cloth plate may be removed from the machine without disturbing the throat plate and the machine operated for stitching.

5 4. In a sewing machine, a bed, a bracket rising therefrom and disposed at one side of the line of feed, a support mounted on said bracket and having spaced parallel members extending transversely of the line of feed, a

10 throat plate secured to said members and bridging the space therebetween, and a cloth plate above said support and extending about said throat plate.

15 5. In a sewing machine, a bed, a bracket rising therefrom and disposed at one side of the line of feed, a second bracket rising from said bed at the other side of the line of feed, a support mounted on said brackets and having spaced parallel members extending transversely of the line of feed, a throat plate secured to said members and bridging the space therebetween, and a cloth plate above said support and extending about said throat plate.

20 25 In testimony whereof, I affix my signature.
FREDERICK F. ZEIER.
